UNITED STATES PATENT OFFICE

2,183,113

FIRE MAT

Frank Willard Bennett, Decatur, Ga.; dedicated
to the free use of the People of the United
States of America

Application June 2, 1938, Serial No. 211,326

4 Claims. (Cl. 169—1)

(Granted under the act of March 3, 1883, as
amended April 30, 1928; 370 O. G. 757)

This application is made under the act of
March 3, 1883, as amended by the act of April
30, 1928, and the invention herein described, if
5 patented, may be manufactured and used by or
for the Government of the United States of
America for governmental purposes without the
payment to me of any royalty thereon.

I hereby dedicate the invention herein de-
scribed to the free use of the people of the
10 United States of America to take effect on the
granting of a patent to me.

This invention relates to fire extinguishers
and is more particularly concerned with a device
for extinguishing surface forest or grass fires.

15 One of the objects of this invention is the pro-
vision of a device as an auxiliary means for
quickly controlling fast spreading surface fires,
such as the grass fires commonly occurring in
some of the southern and western regions of
20 the United States.

Another object of this invention is the provi-
sion of such a device which is inexpensive, of
simple construction and operation, and which
does not require a large number of operators.

25 A further object of this invention is to provide
a device of the character mentioned which can
be conveniently transported or stored in a small
space.

The following description, considered together
30 with the accompanying drawing, will disclose this
invention more fully and further objects and ad-
vantages thereof will be apparent.

In the drawing:

Figure 1 is a plan view of an embodiment of
35 this invention.

Figure 2 is a cross-sectional view of Figure 1.

Figure 3 is an isometric view showing the de-
vice in a compact roll for storage.

Referring with more particularity to the draw-
40 ing in which like numerals designate like parts,
the device is in the form of a large mat and is
fabricated of a bottom piece 1, and a top piece
2, both of canvas, or other suitable material
of a semi-permeable nature. These two pieces
45 are secured together at their outer edges by
stitching, or otherwise, to form a confined space
between them, and the grommets 3, 3, 3, 3, are
disposed one in each corner. The opening 4 is
disposed in one corner of the device for introduc-
50 ing a liquid into the confined space, and a slide
fastener 5 is provided for closing the opening.
To insure proper distribution of the liquid
throughout the confined space, broken seams 6
are stitched, some horizontally and some verti-
55 cally, substantially as shown.

Two lengths of rope or cable 7, 7 are attached
to each corner of one end of the device through
the grommets above-mentioned.

The operation of this invention is as follows:

Through the opening 4 a non-inflammable
liquid such as water, or a 10% solution of mono-
ammonium phosphate is poured until the con-
fined space is filled and the opening is then 5
closed by means of the slide fastener 5. Two
operators straddling a surface fire drag the de-
vice across the fire by means of the cables 7, 7.
While this requires one of the operators to walk
inside the firm zone, this is possible without in-
jury in the types of fire to which this device
is adapted. The smothering effect of the drag
plus the dampening effect of the water, or other
chemical solution employed, extinguishes the fire
as the mat is dragged along the ground. 15

Having thus described my invention, I claim:

1. A portable mat for extinguishing surface
fires, said mat comprising a top canvas section
and a bottom canvas section congruent to said
top section, said sections being secured together 20
at their outer edges to form a confined space
therebetween, means for introducing a fire extin-
guishing liquid in said confined space, broken
stitches securing said sections together at ran-
dom points, and cables for dragging said mat
25 over a surface fire.

2. An article of manufacture comprising a mat
having a top canvas section and a bottom canvas
section congruent to said top section, said sec-
tions being secured together at their outer edges
30 to form a confined continuous space therebe-
tween, broken stitches securing said sections to-
gether at random points, an opening through one
of said sections for introducing a fire extin-
guishing liquid in said confined space, and means for
35 closing said opening.

3. An article of manufacture comprising a mat
having a top canvas section and a bottom canvas
section congruent to said top section, said sec-
tions being secured together at their outer edges
40 to form a confined continuous space therebe-
tween, broken stitches securing said sections to-
gether at random points, an opening through one
of said sections for introducing a fire extin-
guishing liquid in said confined space, and a 45
slide fastener for closing said opening.

4. An article of manufacture comprising a mat
having a top canvas section and a bottom canvas
section congruent to said top section, said sec-
tions being secured together at their outer edges
50 to form a confined continuous space therebe-
tween, broken stitches securing said sections to-
gether at random points, an opening through one
of said sections for introducing a fire extin-
guishing liquid in said confined space, a slide 55
fastener for closing said opening, and cables for
dragging said mat over a surface fire.

FRANK WILLARD BENNETT.
